3 Claims. (Cl. 74—724)

1

A device for driving the turntable of a gramophone can be constructed in different ways. The greater the requirements, put at the constancy of the velocity and the value of the mechanical noise level, the more accurate and the more expensive the drive will be.

Physiological experiments have shown, that the variations in the velocity have to be less than 1 pro mille of the average speed. The same requirement is also put to the driving mechanism, which means very accurate manufacture and punctual finish.

In principle an extremely good driving mechanism can consist of a high running synchro-motor with wormgear. These parts can be made with the required accuracy.

The invention creates the possibility to construct gramophones with one or more different speeds, using original wormgears and keeping the greatest simplicity. Therefore the driving mechanisms are constructed as loose units and consist of a small synchromotor, wormcase with worm and wormwheel gearing, a ballbearing and a freewheel coupling. The only difference among the said units is the proportion of the worm and wormwheel; in other words, the worm:wormwheel proportion stipulates the speed of the turntable.

The said units fit into and upon each other like bricks in a toy box and in this way it is possible to mount up gramophones for 1, 2, 3 and 4 speeds, in accordance with the requirements.

In contra-distinction with known constructions, the wormwheel has not been borne on an axle, but on a fixed, central and hollow core on the bottom of the wormcase by means of a ballbearing, which bearing affords by its construction a very great stability to the said wormwheel.

The unit case has been constructed with a ridge, on which the synchromotor has been connected by means of three screw-nuts. The free axle-end of the motor with the worm mounted on it, is directed into the wormcase, by which the worm can be brought into contact with the wormwheel. The three screw-nuts by which the motor has been connected on the ridge of the wormcase, have ample holes at their disposal so that it is possible to remove the motor with the worm in any direction in a vertical field. Herewith a correct mounting between worm and wormwheel can be effected.

As the wormcase is entirely open at the top and perfectly within easy reach, the mounting can be made very simply and easy to control. The intention is that this mounting is performed by the factory. It may be left to the user to mount the units, constructed in this manner, into complete drives with the necessary accessories.

The connection of the wormwheel with a ball-

2

bearing on a central core of the wormcase is a completely mounted transmission, which can simply be set turning and can be controlled only by switching in the motor. The core rises far above the oillevel and excludes by its very construction the leaking or flowing away of oil. The worm however, can yet take oil enough in order to lubricate the wormwheel and itself sufficiently.

10 As for a drive at different speeds more driving-units are required, in which action always only one unit must be working, every unit is equipped with a freewheel-coupling. This accessory works by means of balls or rolls, which will be locked 15 in between the two parts, which are to be coupled with the turning direction required and with which the rolls or balls will function as a stiff coupling. One part will work as the driving accessory, the other part as the driven one. If 20 however the driven part will be e. g. an axle, driven into the same turning direction by any other cause, then the rolls or balls will decouple themselves automatically and the original driving accessory will stop.

25 According to the invention a complete drive consists besides units of a bottom- and a top-shield and a secondary axle. The said shields cover the units completely and contain moreover the ballbearing with which the secondary 30 axle is borne.

35 The secondary axle can be pushed through the hollow core of the wormcases and operates without contact and acts as the driven part of every freewheel-coupling in every unit and is centrally borne by the ballbearings in the two shields.

40 The freewheel-coupling has been connected on the top of the wormwheel. For a satisfying operation it is the very condition that the said freewheel-coupling is connected with the said wormwheel in an elastic way. This condition can be accounted for by the following reason. As already known, the said wormwheel is substantially borne with a ballbearing on the central and hollow core of the unit case. The secondary 45 shaft is substantially supposed with the two ballbearings in the two shields. Although shields and units fit into and on each other with great accuracy so that it may be expected that the secondary shaft will come centrally in its correct place, it will be necessary to keep account with any eccentricity in practice as a consequence of inaccuracies in the manufacturing.

50 Although the deviations will not be greater than 10 microns, it would be enough to introduce undesirable effects as irregular turning of the secondary shaft and great wear in the freewheel-couplings. By connecting the freewheel-coupling with the wormwheel in an elastic way, such undesirable effects can be avoided and any ex-

centricity or other deviations can be caught imperceptibly.

The rolls or balls in the freewheel-couplings are locked in a cage, by which they cannot get away. However, they are able to make contact through holes with those parts of the system, which must be coupled, or decoupled. So the freewheel-couplings stay intact during transport or mounting of the units. Although the principle in such a manner of the freewheel-couplings is not quite original, the special construction adapted by the units is of great importance.

It must be known, that the secondary shafts according to the invention have been adapted and manufactured in such a way, that it is possible without any trouble to push them through the units, freewheel-couplings and shields by hand, with which a correct position and collaboration with these freewheel-couplings is reached automatically. That portion of those parts of the shaft operating in and with the freewheel-couplings are therefore manufactured on one diameter, except the lower end, which is conical. In this way it is a very simple manipulation to bring in and to push the shaft through the units and the freewheel-couplings. When the shaft is brought in and pushed through, the rolls of balls of the respective freewheel-couplings are pushed away and are of not any hindrance. As the secondary shaft itself, in contradistinction with known constructions, is coupled with the rolls or balls directly, it is necessary to harden and to grind the shaft in that very place.

The normal process of hardening by heating and cooling has the risk of warping. Moreover the shafts would have to be hardened along nearly their whole length. Therefore a much better and cheaper method is recommended with which the shafts are chromed and polished only in the places, which come into contact with the rolls or balls of the freewheel-couplings. The intermediate parts may remain unpolished.

Now follows an example for a mounting of a drive at three different speeds. First the bottom-shield. Upon this a unit, say for 33,33 R. P. M., is mounted; next a unit for 45 R. P. M. and upon this a unit for 78 R. P. M. Now the respective motors of the three units are fixed under angles of 120 degrees.

A secondary shaft of a fixed length and suitable for a drive at three speeds is now pushed through the units and freewheel-couplings and is pressed with the lower end into the ballbearing of the bottomshield.

Then the top-shield is pushed over the shaft and is pressed on the highest unit. Three screw-bolts are pushed through holes in the wall of each unit case and through the shields and with rings and nuts the units and shields are pressed upon each other just like electro-motors. Herewith a drive at three speeds is ready now.

In this simple way a user can mount according to his wishes and according to what is wanted and he can equip studios and other technical rooms in a most modern way. The drive mounted in such a manner can be coupled with the turntable in a well known way.

The operation is as follows. If for example the lowest unit for 33,33 R. P. M. is switched on, then the freewheel-coupling will be taken up by the wormwheel of that unit; the rolls or balls in the freewheel-coupling and the secondary shaft are going to act like a stiff coupling by which the turntable is driven in a perfectly reliable manner. At the same time the rolls or balls in the

freewheel-couplings of the remaining units decouple automatically, because the shaft acts there as the driving part. In this way it is possible to switch over from one unit, or speed to the other at once. Even mistakes in switching, by which two or three units would be set into action at the same time, can have no disadvantageous results. The unit having the highest speed will have the leading part in the action. It drives the secondary shaft and also the turntable, while the shaft remains uncoupled automatically in respect of the other units.

A more detailed description of the invention will follow hereunder in connection with the pictures.

Fig. 1 is a top-view of a complete driving-unit constructed in this invention.

Fig. 2 is a cross-section via line II-II of Fig. 1;

Fig. 3 is a cross section of a complete driving system for two speeds. The part freely projecting of the secondary shaft has been represented in this picture as broken off; the shaft can be made as long as necessary for a coupling with the turntable.

Fig. 4 represents the construction and action of a freewheel-coupling according to the invention on a larger scale.

A driving-unit according to Figs. 1, 2 and 3 consists of a synchromotor 1 of the one-phase-type with condenser-starting. Said motor 1 has been connected on the ridge of the unitcase 3 by means of three screw-bolts 2. A worm 4, mounted on the free shaft-end of the said motor, directing into the wormcase is in collaboration with a wormwheel 5, which has been supported on a ballbearing 6, which bearing affords by its construction a very great stability to the said wormwheel 5.

Said screw-bolts 2 have ample holes at their disposal, so that it is possible to remove the motor 1 with worm 4 over the ridge of the unitcase 3 in any direction in a vertical field and to reach a correct mounting and collaboration between worm 4 and wormwheel 5.

The connection of the wormwheel 5 with the ball bearing 6 on a fixed, central and hollow core on the bottom of the unit case 3, acts as a complete mounted gearing, which can simply be set turning and can be controlled, whereto the unit case 3 is entirely open at the top and perfectly within easy reach.

Said central core on the bottom of the unit case 3 rises above the oil level and excludes the leaking or flowing away of oil. The worm 4, however, can yet take oil enough in order to lubricate the wormwheel 5 and itself sufficiently.

As for a drive at different speeds more driving-units are required, in which action always only one unit must be working, every unit is equipped with a freewheel-coupling. The construction and the operation of a freewheel coupling can be explained most clearly with Figure 4.

The coupling consists of a segment-disc 9 of hardened steel, said disc being, if desired, locally ground. The three segments and the disc form one unit obtained by fraising and grinding the disc. The disc 9 lies with sufficient play around the secondary shaft 20. Between said shaft and each segment of the disc 9 hardened steel rolls 10 are provided. Said rolls 10 are under light pressure by means of the sleeves 11 and the springs 12. The rolls 10, sleeves 11 and springs 12 are arranged in a cage 13, enclosed between

the three segments of the disc 9 and fastened thereto by means of three screws 14.

The sleeves 11 and the springs 12 can be introduced from the outside into the cage 13 and can be secured by means of the screws 15. The rollers 10 can move freely in the spaces of the cage and through apertures can make contact with the shaft 20 and the three segments of the disc 9.

The apertures however, are too small to allow the passage of the rollers 10, so that they cannot drop out during transport or during assemblage of the device.

It is sufficient to pass the secondary shaft 20 through the cage 13 and the disc 9 to allow the coupling to function when the disc 9 is rotated clockwise, e. g. by driving same by the worm-wheel 5, the rollers 10 close up between the shaft 20 and the segments of the disc 9 and act as a rigid coupling so that the shaft 20 is rotated in an entire reliable manner.

If on the other hand the shaft 20, however, is driven clockwise, e. g. by means of one of the further units, the rollers 10 are automatically released and the shaft can rotate freely. The driving units are completed by a lower shield 16, provided with a ball bearing 17 and by an upper shield 18 provided with a ball-bearing 19 and further with the secondary shaft 20 and tensioning bolts 21 with rings 22 and nuts 23.

The shields 16 and 18 form a perfect closure for the driving units. The ball-bearings 17 and 19 serve as a centric support for the secondary shaft 20. Said shaft passes through the hollow core of the unit cases 3, the cage 13 and the disc 9 without contact and the only contact with a driving unit is obtained by the rollers 10 of each freewheel-coupling.

A condition for the correct operation of the system is that the freewheel-coupling, i. e. the segment disc 9, is elastically coupled with the wormwheel 5, said wormwheel being supported independently on the ball bearing 6 on the central core of the unit-case 3.

The secondary shaft 20 is supported independently by means of the ball-bearings 17 and 19 in the shields 16, 18.

Through the shields 16, 18 and the universal driving units slidably fit in and on each other and it may be assumed that the secondary shaft 20 can be mounted exactly centered in practice very small deviations, which can occur in the manufacture, have to be taken in consideration. Small deviations can give rise to undesired phenomena such as unsmooth running of the shaft 20 and wear in the freewheel-couplings.

An important characteristic feature of the freewheel-coupling according to the invention is that the segment disc 9 is connected with the worm-wheel 5 by means of an elastic coupling. Said coupling can consist of a flat annulus 24 of pliant synthetic rubber, being vulcanised centrally to the disc 9 and the wormwheel 5. Said coupling may consist of rubber pads or steel springs. A flat ring is very simple and can take up important deviations.

The special construction of the disc 9 enables to introduce the secondary shaft without more by hand through the mounted units in which case automatically contact and the correct cooperation with the freewheel couplings is obtained.

The part of the shaft 20 within the units is finished on one single diameter with the exception of the lower end, which is conical so that it is very simple to pass said shaft through the

units and the couplings. In introducing the shaft 20 the rolls 10 are pushed laterally and do not form any obstruction.

The shaft 20 itself being coupled with the rolls 10 without the aid of other components it is necessary to harden and to grind the shaft locally.

The normal hardening process by means of heating and cooling shows the risk of warp, which cannot always be corrected by grinding. In that case it would be necessary to harden the shafts over the whole length.

A characteristic feature of the shafts according to the invention is that only at the place of contact with the rolls 10 the shafts are hard-chromised and ground. The further parts need no working. The units and the shields 16, 18 are pulled together by means of a number of draw-bolts 21, washers 22, and nuts 23.

For that purpose the walls of the unit cases 3 are provided with a number of e. g. six continuous channels in such a way, that for a driving mechanism with one single number of revolution two draw-bolts, for a mechanism with two different numbers of revolution three bolts and for a mechanism with four numbers of revolution four draw-bolts can be used.

I claim:

1. A synchro-motor and worm-transmission driving mechanism for the turntable of a phonograph comprising a plurality of separate driving units each corresponding to a different driving speed, and a driving shaft provided with a ball-bearing therefor, each driving unit consisting of a synchro-motor, a worm-transmission, a free-wheel coupling and an elastic coupling between said worm-transmission and said free-wheel coupling, said worm-transmission comprising a worm-wheel, a cylindrical housing about the driving unit provided with a bottom plate, said housing forming a flat unit in which the free-wheel coupling is arranged, said worm-wheel being supported on a ballbearing and centrally mounted on said cylindrical housing, each of said driving units together with their respective couplings being rotatably engaged against the driving shaft to fit against each other, and a closing shield encasing the ends of the plurality of driving units.

2. A driving mechanism as in claim 1 wherein said driving shaft is vertically disposed in said housing and wherein said housing is provided with a concentric inner wall surrounding said shaft, the upper ridge of said wall projecting beyond said transmission and said ballbearing to provide an annular oil container for the moving elements of the driving mechanism.

3. A driving mechanism as in claim 1 wherein each freewheel coupling consists of a metal ring coupled to the corresponding wormwheel with a rubber ring, said freewheel coupling being provided with segmented members and springs pressing said segmented members against an annular portion of the surface of said shaft, and wherein said shaft is hardened by chromizing.

MARIUS LEONARD VAN OVEREEM.
